UNITED STATES PATENT OFFICE.

OSWALD DUDA, OF HOUSTON, TEXAS, ASSIGNEE, BY MESNE ASSIGNMENTS, TO REED
ROLLER BIT COMPANY, A CORPORATION.

DEEP-WELL-DRILLING APPARATUS.

Application filed May 11, 1922. Serial No. 560,163.

To all whom it may concern:

Be it known that I, OSWALD DUDA, a citizen of the United States, and resident of Houston, in the county of Harris, in the State of Texas, have invented certain new and useful Improvements in Deep-Well Drilling Apparatus, of which the following is a specification.

The invention relates to deep well drilling apparatus and particularly to means for pumping lubricant to the cutters thereof. The pump is embodied in the apparatus itself and derives its power from the motion of the apparatus in the wall.

15 The invention consists in the features and combination and arrangement of parts hereinafter described and particularly pointed out in the claims.

In the drawings—

20 Fig. 1 is a central, vertical sectional view of the apparatus, it being noted, however, that the section through the cutters is taken upon two planes at 90° apart in relation to each other, so that one of the inclined rotary cutters appears and also one-half of the cross roller cutter is shown.

Fig. 2 is a vertical sectional view on an enlarged scale of the pumping apparatus combined with a portion of the lubricant holder.

25 In these drawings—1 indicates the drill stem; 2, one of the inclined side cutters; 3, a portion of the cross roller cutter; 4 a lubricant holder in the form of an elongated tube arranged coaxially with the drill stem and seated by its screw threaded lower end upon a socket member 5 which in turn is seated in the upper end of the reamer block 6 which carries reamer cutters 7. The flushing fluid forced down through the drill stem passes along the annular space 8 between the drill stem and the lubricant holder 4 and thence through ports 9 and a central passage 10 of the socket member and through the central channel 11 of the reamer block, from whence it passes through passages 12 in the drill head to the cutters to flush the same, as is well known to those skilled in the art.

30 The socket member 5 is provided with passages, one of which is indicated in dotted lines at 13, for conducting the lubricant from the holder 4 by way of the annular passage 14 to suitable conduits that lead the lubricant to the parts to be lubricated, such as the passage 15 which di-

rects the lubricant to a central chamber 16 from whence it is distributed through passages such as 17 to the bearings of the cutters. Other passages such as 18 conduct the lubricant to the journal pins of the reamer 60 cutters 7.

At 19 is shown a piston in the lubricant holder and when this is forced downwardly the lubricant is forced through the various passages mentioned to the parts to be lubricated.

For forcing the piston 19 downwardly, a portion of the flushing fluid is forced into the top of the lubricant holder above the piston 19 and in order to accomplish this result a pumping arrangement is employed which includes a piston 20, a cylinder 21 within which the piston reciprocates coaxially of the lubricant holder. The cylinder 21 is carried by a block 22 which is 70 screw threaded into the upper end of the lubricant holder 4. This block or partition member has a screw threaded seat at 23 receiving the shell of a chamber 24 which is arranged as a coaxial extension of the lubricant holder, the said chamber being closed at its upper end by a cap member 25 screw threaded into connection therewith. At 26 there is an inlet for flushing fluid to the chamber 24, this inlet being protected by 80 a screen 27 of any suitable form held in place by a screw threaded ring 28. The flushing water passes to the chamber 24 through a port 29 after passing through the screen.

85 The piston 20 is connected with a rod 30 the upper end of which is reduced and is slidably guided at 31 in the cap member 25. On this rod a weight 32 is mounted to have slight longitudinal movement in relation to the rod and the rod is provided with a flange 33 at or near its lower end, and a nut 34 at its upper portion between which and the collar the weight 32 is arranged, it being noted, as above stated, that the weight is 1 loosely mounted on the stem and can have slight longitudinal movement between the nut 34 and the collar 33. At each end of this weight a spiral spring is arranged as shown at 35, each of these springs bearing at 1 one end upon the weight and at its opposite end upon the adjacent stationary structure such as the block 22 and the cap member 25. The weight is of somewhat smaller diameter than the interior diameter of the chamber 24 1

and it is of less length than the said chamber so that room is provided for longitudinal movement of the stem or rod 30 together with the weight, in relation to the chamber 5 containing these parts.

The piston 20 is provided with an inlet port 36, extending mainly coaxially of the piston and having a lateral branch at its upper end so that this piston will act in the 10 nature of an inlet valve whereby when the piston is raised so that the mouth 36' of the port 36 is above the upper surface of the block 22, then the flushing fluid will pass from the chamber 24 into the cylinder 21, 15 whereas when the piston is lowered, as shown in Fig. 2, the inlet of the flushing fluid will be cut off from the cylinder 21.

The cylinder is provided with a discharge valve and as an example of this a valve 37 20 is shown adapted to be seated at 37' against the block 22 and this valve is pressed upwardly to closed position against this seat by a spring 38, the lower end of which rests upon a screw plug 39 seated in the block 22. 25 The discharge valve is guided in the block, but it controls the discharge port leading from the cylinder 21.

The fluid after passing this discharge 30 valve, enters the top of the lubricant holder by way of the port 40.

In the operation of the apparatus the drill stem derives a vertical vibratory movement due to the roller cutter at the lower end thereof running over the uneven surfaces 35 being cut, or when running over smoother surfaces the vibratory action of the drill stem will be due to the formation of the cutters which are provided with teeth on their peripheries. Supposing the parts to be in 40 the position of Fig. 2 and with the drill stem vibrating vertically and supposing the drill stem is at the upper end of its vibratory stroke, the discharge valve will be closed and the combined pump piston and 45 inlet valve 20 also will be closed. When the upper limit of this vibratory stroke of the apparatus is reached and the downward stroke begins, the weight 32 will not respond immediately to this change in direction of 50 the stroke, due to its inertia or momentum, and hence it will assume a position relative to the drill stem in which it will be raised so as to uncover the port 36', and this will allow the water to flow into the pump cylinder 55 from the chamber 24, it being noted that the relative up stroke of the piston 20 while the discharge valve is closed, creates a vacuum under the piston 20 in the chamber 21. Now when the movement reverses, that is by 60 the drill stem rising, the weight with its piston will again lag in respect to the movement of the stem, thus assuming a lowered position in relation to said stem, and causing the piston 20 to force the water from the cylinder 21 past the spring pressed discharge 65

valve 37 which will open during this pumping stroke of the piston 20 and the weight 32, and thus the water will be forced from the cylinder 21 past the discharge valve into the upper end of the lubricant holder where, acting under the pressure from this pumping stroke upon the piston 19, this will be forced down to force the lubricant from the holder through the various passages to the parts to be lubricated. I do not limit myself to 70 the source from which the water is derived to be forced by the pump into the upper end of the lubricant holder and it will be understood that the above specification and drawings are presented in an illustrative way 75 and are not to be considered as restrictive upon the scope of the invention, which is defined by the appended claims. The springs at opposite ends of the weight cushion the stroke of this weight and also aid in moving the weight in opposite directions, for instance, when the weight moves upwardly relative to the drill stem the upper spring is compressed and reacts at the proper time to force the weight with its rod and piston 80 downwardly and the same is true when the downward movement of the weight takes place, namely, it compresses the lower spring and upon reversal of the action this spring aids in throwing the weight upwardly. 85

As before stated, the weight has some slight movement freely on the rod 30 so that in its action in either direction it will have a small measure of free play and then come against the collar or the nut so as to exert a hammer blow thereon to operate the rod 30 together with its piston valve 20 in either one direction or the other. It will be seen from the above that the pump is 90 operated by reason of the vibratory movement imparted to it from the drill stem and the action of this pump in its vibratory movements is out of time with the vibrations of the drill stem and hence the pumping action results, this being due to the relative 95 movement between the lubricant holder and the parts attached thereto and the weighted piston, it being understood that the lubricant holder and its attached parts conform 100 in their vertical vibratory movements exactly with those of the drill stem because they are permanently attached thereto. 105

The fluid for operation in the pump can be derived from outside the drill stem. 110

What is claimed is:—

1. In deep well drilling apparatus, a drill stem, cutters, a lubricant holder, and a pump for forcing the lubricant to the parts to be lubricated, carried by the apparatus and operated by the vibration of the apparatus, due to its working against the material being cut, said pump having a piston reciprocating relative to the lubricant holder substantially as described. 125

2. In deep well drilling apparatus, a drill 130

- stem, cutters, a lubricant holder, and a pump for forcing the lubricant to the parts to be lubricated, carried by the apparatus and having a piston reciprocated relative to the lubricant holder by the vertical vibration of the apparatus, due to its working against the material being cut, substantially as described.
3. In deep well drilling apparatus, a drill stem, toothed rotary cutters giving to the drill stem vertical vibratory motion during the cutting operation, a lubricant holder and a pump for forcing the lubricant to the cutter bearings having a piston reciprocated relative to the lubricant holder by the vibratory motion of the drill stem, substantially as described.
4. In deep well drilling apparatus, a drill stem, cutters, a lubricant holder, and a pump for forcing the lubricant to the parts to be lubricated, carried by the apparatus and operated by the vibration of the apparatus, due to its working against the material being cut, said pump forcing fluid into the holder, substantially as described.
5. In deep well drilling apparatus, a drill stem, cutters, a lubricant holder, and a pump having a vertically reciprocatory plunger, carried by the apparatus and subject to the vibrations of the apparatus working in the well for operating the pump, substantially as described.
6. In deep well drilling apparatus, a drill stem, cutters, a lubricant holder, and a pump having a vertically reciprocatory plunger, carried by the apparatus and subject to the vibrations of the apparatus working in the well for operating the pump, said plunger being disposed coaxially with the drill stem and the lubricant holder, substantially as described.
7. In combination in deep well drilling apparatus, a drill stem, a lubricant holder arranged coaxially with the stem, a pump cylinder, a discharge valve for said cylinder opening into the lubricant holder, a piston operating in the cylinder, means for the inlet of fluid into the cylinder when the piston rises, a weight connected with the piston, said weight being operated vertically by the vertical vibration to which the drill stem is subjected while working in the well, to thereby operate the piston, substantially as described.
8. In combination in deep well drilling apparatus, a drill stem, a lubricant holder arranged coaxially with the stem, a pump cylinder, a discharge valve for said cylinder opening into the lubricant holder, a piston operating in the cylinder, means for the inlet of fluid into the cylinder when the piston rises, a weight connected with the piston, said weight being operated vertically by the vertical vibration to which the drill stem is subjected while working in the well, to thereby operate the piston, substantially as described.
9. In combination in deep well drilling apparatus, a drill stem, a lubricant holder arranged coaxially with the stem, a pump cylinder, a discharge valve for said cylinder opening into the lubricant holder, a piston operating in the cylinder, means for the inlet of fluid into the cylinder when the piston rises, a weight connected with the piston, said weight being operated vertically by the vertical vibration to which the drill stem is subjected while working in the well, to thereby operate the piston, and spring means acting upon the weight to cushion the action of the same, substantially as described.
10. In combination in deep well drilling apparatus, a drill stem, a lubricant holder, arranged coaxially with the stem, a pump cylinder, a discharge valve for said cylinder opening into the lubricant holder, a piston operating in the cylinder, means for the inlet of fluid into the cylinder when the piston rises, a weight connected with the piston, said weight being operated vertically by the vertical vibration to which the drill stem is subjected while working in the well, to thereby operate the piston, and a spring at each end of the weight to cushion the action of the same and to force said weight longitudinally, substantially as described.
11. In combination in deep well drilling apparatus, a drill stem, cutters, a lubricant holder arranged coaxially within the drill stem, a pump piston and cylinder arranged coaxially with and at the upper end of the lubricant holder, a weight connected with the upper end of the piston, a chamber in which said weight moves, a port for inlet of fluid to said chamber, a discharge valve for controlling the outlet of fluid from the cylinder to the lubricant holder, and means for the inlet of fluid to the cylinder from the said chamber, substantially as described.
12. In combination in deep well drilling apparatus, a drill stem having vertical vibration, a lubricant holder within the stem, and a pump operated from the vibratory movement of the stem, said pump consisting of a cylinder and piston and means for the inlet and discharge of fluid to the cylinder to be forced into the upper end of the lubricant holder, a rod connected with the piston, a weight mounted on said rod to have movement along the rod, and means on the rod against which the weight abuts to effect a hammer blow thereon, substantially as described.
13. In combination in deep well drilling apparatus, a drill stem, a lubricant holder, a piston therein to force the lubricant to the

parts to be lubricated, a pump operated by the vibration of the drill stem, said pump forcing fluid into the lubricant holder above the piston, substantially as described.

14. In combination in deep well drilling apparatus, a drill stem, a lubricant holder arranged coaxially therewith, a block closing the upper end of the lubricant holder, a chamber the shell of which is supported on the block, a piston reciprocating in the block and having a rod extended through the said chamber, a weight mounted on the rod, means for the inlet of fluid into the top of the chamber and means for the inlet of said fluid from said chamber to the cylinder in

which the piston reciprocates, and a discharge valve controlling the outlet of fluid from the piston chamber into the upper end of the lubricant holder, substantially as described. 20

15. In combination in deep well drilling apparatus, a drill stem, a coaxially arranged lubricant holder, and a pump operated by the vibration of the drill stem, said pump taking the flushing water from the drill stem and forcing it into the upper end of the lubricant holder, substantially as described. 25

In testimony whereof I affix my signature.
OSWALD DUDA.
